9274

UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S OVERSKIRT.

SPECIFICATION forming part of Design No. 15,133, dated July 8, 1884.

Application filed May 23, 1884. Term of patent 3½ years.

To all whom it may concern.

Be it known that I, SARAH JANE SHIELS, of the city, county, and State of New York, have invented and produced a new and original Design for a Pattern of a Lady's Overskirt, (numbered 9,274;) and I do hereby declare that the engraved prints accompanying this specification convey to any one accustomed to using paper patterns a clear understanding of how to a garment made up by the pattern will appear.

The design shows a deep, square back drapery, exhibiting draping-plaits in its front edges and loopings at the center; a deep, right-side drapery that exhibits draping-plaits in its back edge, and describes a point at its lower

front corner; a left-side drapery that appears to overlap the right-side drapery for a part of its length, and exhibits draping-plaits extending from its back edges, and a point at its lower front corner, and an overlapping left-side drapery smaller than but similar in outline to the left-side drapery just described.

What I claim as my invention, and desire to secure by Letters Patent, is--

The design for a lady's overskirt, as shown in the engraved prints accompanying this specification.

SARAH JANE SHIELS.
